ALFRED J. A. PETERSON AND FLOYD B. KNISKERN, OF WILKINSBURG, PENNSYLVANIA, ASSIGNORS TO WESTINGHOUSE ELECTRIC & MANUFACTURING COMPANY, A CORPORATION OF PENNSYLVANIA.

CIRCUIT-INTERRUPTER SYSTEM.

Application filed March 13, 1924. Serial No. 698,889.

To all whom it may concern:

Be it known that we, ALFRED J. A. PETERSON, a citizen of the United States, and a resident of Wilkinsburg, in the county of Allegheny and State of Pennsylvania, and FLOYD B. KNISKERN, a citizen of the United States, and a resident of Wilkinsburg, in the county of Allegheny and State of Pennsylvania, have invented a new and useful Improvement in Circuit-Interrupter Systems, of which the following is a specification.

Our invention relates to circuit interrupter systems and particularly to the control of the operating motor of the system.

One object of our invention is to provide a system of circuit interrupters that are actuated in common by a motor that shall have means for automatically regulating the electrical energy supplied to the motor in accordance with the number of circuit interrupters that are to be actuated at any given time.

Another object of our invention is to provide a circuit interrupter system, in which a single motor is employed to selectively actuate any one or all of a group of circuit interrupters, that shall have means for automatically regulating the current supplied to the motor in accordance with the number of circuit interrupters that are to be moved from their open to their closed position at any given time.

It is also an object of our invention to provide a circuit interrupter system, in which one or more circuit interrupters are simultaneously operated from a single motor, that shall have means to control the energy input to that motor in accordance with the number of circuit interrupters to be actuated, thereby eliminating overloading of the motor.

It is a further object of our invention to provide a circuit interrupter system that shall be operated by a single motor, the energy supplied to which is automatically controlled by the number of circuit interrupters to be moved at any given time.

The present application is an improvement over the circuit interrupter system shown and described in the copending application of A. J. A. Peterson, Serial No. 681,785, filed Dec. 20, 1923, and which is assigned to the Westinghouse Electric &

Manufacturing Company. In that application there is shown and described a mechanism for connecting any one or all of a group of circuit interrupters to a common operating mechanism. That application describes, in detail, the mechanical and electrical disposition of parts necessary to accomplish the desired results.

In accordance with the present invention, we place a variable resistor in circuit with the motor and connect sections of the resistor to the several circuit interrupters in such manner that a section of the resistor is short-circuited when any one of the circuit interrupters is in its open position thereby permitting an increased amount of energy to be applied to the motor. Provision is also made for interrupting the circuit connections necessary to the foregoing objects when it is desired that any one of the circuit interrupters shall be locked in its open position.

The single figure of the accompanying drawing is a diagrammatic view of circuits and apparatus embodying our invention.

Our invention comprises, in general, a plurality of circuit interrupters 1, 2 and 3, that control electrical distribution circuits 4, the several circuit interrupters being provided with mechanism for controlling their connection to a common operating shaft 5, and the electromagnet or motor 6. The motor 6 is connected in circuit with a variable resistor 7 comprising sections 8, 9 and 11 that are connected to the different circuit interrupters 1, 2 and 3, in such manner that the amount of resistance in series connection with the motor 6 is dependent upon the number of circuit interrupters that are in their closed position.

Each of the circuit interrupters 1, 2 and 3 is provided with a bridging member 12 that engages stationary contact members 13 when the circuit interrupter is in its closed position. A link mechanism 14, terminating in a latch 15 supports and actuates the bridging member 12. An arm 16 is connected to the shaft 5, and when the arm is in engagement with the latch 15, it serves to actuate the bridging member 12 into engagement with the stationary contact members 13. A tripping device 17 that may be controlled either manually by a handle 18, or electrically by a remotely located switch

19, is connected to each of the latching mechanisms 15. Similarly, a lock-out mechanism 21 having a handle 22 for manual operation, a remotely disposed switch 23 for the electrical control thereof and a spring biasing latch 24 is associated with each of the arms 16. A releasing electromagnet 25 that is remotely controlled, as by a switch 26, is provided for tripping each of the latch mechanisms 24. Each electromagnet may be provided with a handle for the manual operation thereof, if desired. Springs 27 and 28 are provided for normally keeping the latch members 15 in engagement with the arms 16, respectively, unless they are prevented from so doing by the operation of the mechanisms 17 and 21, respectively.

20 The motor 6 is shown in the accompanying drawing in the form of an electromagnet that breaks its own circuit by a pilot switch 31 at the limits of its movement of the shaft 5. It is obvious that a rotating motor may be substituted for the electromagnet by 25 changing the connection to the shaft 5. In any event, the form of the motor employed does not materially effect the objects of the present invention.

20 Mounted on the link mechanisms 14 of the circuit interrupters 1, 2 and 3, are back contact switches 34, 35 and 36, respectively, that are adapted to short circuit the sections 8, 9 and 11, respectively, of the resistor 7 in accordance with which of the circuit interrupters 1, 2 and 3 are in their open position.

25 Each of the lock-out mechanisms 21 is provided with a switch 37 comprising a stationary contact member 38, and a movable contact member 39 carried by the mechanism 21. The circuits between the associated contact switches 34, 35 and 36 and the resistor sections 8, 9 and 11, respectively, are broken by the switch 37 when any circuit interrupter 1, 2 or 3 is latched in its open position, thereby placing the corresponding sections of resistor 7 in series with the motor 6. Conductors 41 and 42 constitute a direct current source of energy for operating the motor 6 and the several coils included in devices 17, 21 and 25.

30 Assuming the circuit interrupters 1, 2 and 3 to be in their open position, as shown in the accompanying drawing, a circuit is completed from the conductor 41, through the back contact switch 36, the switch 37 of the circuit interrupter 3, contact switch 35, the switch 37 of the circuit interrupter 2, contact switch 34 and the switch 37 of the circuit interrupter 1, through the switch 31 and the motor 6 to the conductor 42, whereupon the motor 6 is operated to rock the shaft 5 in a counter-clockwise direction. This movement actuates the circuit interrupters 1, 2 and 3 into their closed positions, 35 where they are held by the link mechanism

14, as described in the above-mentioned co-pending application.

When the circuit interrupters 1, 2 and 3 have moved into their closed positions, the several contact switches 34, 35 and 36 are moved to their open positions, whereupon a circuit is completed from the conductor 41, through sections 11, 9 and 8 of the resistor 7, the switch 31 and the motor 6 of the conductor 42. It will thus be seen that the entire resistor 7 is inserted in series with the motor 6 when all the circuit interrupters are in their closed position. While we have shown but three circuit interrupters connected to the shaft 5, it may be understood that this number may be varied indefinitely.

Assuming the circuit interrupters 1 and 3 to be in their closed position and that it is desired to close the circuit interrupter 2, a circuit is completed that extends from the conductor 41, through the section 11 of the resistor 7, contact switch 35, the switch 37 of the circuit interrupter 2, section 8 of the resistor 7, switch 31 and the motor 6 to the conductor 42. Upon the next rocking movement of the shaft 5, the circuit interrupter 2 is drawn into its closed position and the contact switch 35 is opened. When any one of the circuit interrupters 1, 2 and 3 moves to its open position from any cause whatsoever, the associated contact switch 34, 35 or 36 is automatically closed, thereby short circuiting the appropriate section or sections of the resistor 7.

Assuming the circuit interrupter 3 to be in its closed position, and the circuit interrupter 2 to be locked in its open position, and the circuit interrupter 1 in its open position, an incomplete circuit extends from the conductor 41 through the section 11, and the contact switch 35 to the switch 37 of the circuit interrupter 2, but since the lock-out mechanism 21 of the circuit interrupter 2 is latched in its open position, the foregoing circuit is broken between the contact members 38 and 39 of switch 37, which in effect places the section 9 in series circuit to the motor 6. The completed circuit, therefore, extends from the conductor 41, through sections 11 and 9 of the resistor 7, the contact switch 34, the switch 37 of the circuit interrupter 1, the switch 31 and the motor 6 to the conductor 42. The circuit interrupter 1 is thereupon moved into its closed position.

It will thus be observed that provision is made for short circuiting those portions of the resistor 7 that are associated with the circuit interrupters that are open and not locked out.

By this invention, we are able to operate an indefinite number of circuit interrupters from a single motor without overloading the operating motor.

Various modifications may be made in the device embodying our invention without de-

parting from the spirit and scope thereof and we desire that only such limitations shall be placed thereon as are imposed by the prior art or are specifically set forth in the 5 appended claims.

We claim as our invention:

1. In combination, a plurality of circuit interrupters, a common actuating mechanism therefor comprising a motor, means for 10 selectively connecting and disconnecting each of the circuit interrupters to the actuating mechanism, an impedance device in circuit with said motor and means for varying the effective value of the impedance 15 device in accordance with the operative positions of said circuit interrupters.
2. In combination, a plurality of circuit interrupters, a common actuating mechanism therefor comprising a motor, means for 20 selectively connecting and disconnecting each of the circuit interrupters to the actuating mechanism, an impedance device in circuit with said motor and means for varying the effective value of the impedance 25 device in accordance with the operative position of each of said circuit interrupters.
3. In combination, a plurality of circuit interrupters, a common actuating mechanism therefor comprising a motor, means 30 for selectively connecting and disconnecting each of the circuit interrupters to the actuating mechanism, a resistor in circuit with said motor and means associated with each 35 of said circuit interrupters for varying the effective value of the resistor in accordance

with the operative position of the associated circuit interrupter.

4. In combination, a plurality of circuit interrupters, a common actuating mechanism therefor comprising a motor, means 40 for selectively connecting and disconnecting each of the circuit interrupters to the actuating mechanism, a resistor in circuit with said motor, and a switch associated with each of the circuit interrupters for short-circuiting portions of said resistor in accordance with the number of circuit interrupters 45 that are in their open position.

5. In combination, a plurality of circuit interrupters, a common actuating mechanism therefor comprising a motor, means 50 for selectively connecting and disconnecting each of the circuit interrupters to the actuating mechanism, a resistor in circuit with said motor, and a switch associated with each of the circuit interrupters for short-circuiting portions of said resistor in accordance 55 with the number of circuit interrupters that are in their open position and a second switch associated with the lock-out mechanism of each circuit interrupter 60 for interrupting the circuit connections established by the first named switch when the circuit interrupter is locked in its open 65 position.

In testimony whereof, we have hereunto subscribed our names this 26th day of February, 1924.

ALFRED J. A. PETERSON.
FLOYD B. KNISKERN.
